The ornamental design for a electronic input device, as shown and described.

DESCRIPTION

FIG. 1 is a top-right perspective view of an electronic input device of our new design;

FIG. 2 is a bottom-left perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof.

The broken lines in the drawings show environmental structure and form no part of the claimed design.
